UNITED STATES PATENT OFFICE.

THOMAS J. ARBRON, OF DETROIT, MICHIGAN, ASSIGNOR TO THE PERFECTION APPLIANCE CO., OF DETROIT, MICHIGAN, A CORPORATION OF MICHIGAN.

IRONING MACHINE.

Application filed May 16, 1923. Serial No. 639,275.

To all whom it may concern:

Be it known that I, THOMAS J. ARBRON, a citizen of the United States of America, residing at Detroit, in the county of Wayne and State of Michigan, have invented certain new and useful Improvements in Ironing Machines, of which the following is a specification, reference being had therein to the accompanying drawings.

10 This invention relates to ironing machines and has for its principal object the provision of means operated by the power mechanism to move the shoe from and against the roller.

15 A further object of the invention is to provide a yielding mounting for the shoe whereby it may readily adapt itself to variations in thickness of the material being ironed.

20 A still further object of the invention is to provide a roller which has a free end and which is readily detachable from its driving shaft.

Other and further objects of the invention 25 will appear in connection with the accompanying specification, reference being had to the drawings forming a portion thereof, in which—

Figure 1 is an elevation of a preferred 30 embodiment of my invention, parts being broken away and parts being shown in section;

Fig. 2 is a section on the line II—II of Fig. 1;

35 Fig. 3 is a detail showing a different position of parts of those indicated in Fig. 2;

Fig. 4 is a vertical longitudinal section at right angles to that of Fig. 2;

40 Fig. 5 is a perspective view of a single revolution clutch mechanism;

Fig. 6 is a vertical longitudinal section similar to that of Fig. 4, showing a modified form of the invention, and

45 Fig. 7 is an end elevation of the clutch member and its operating lever used in the modified form.

Upon a suitable wheeled base 1 is mounted a standard 2 upon the upper end of which is a bracket 3 forming a support for a table 4. 50 Above the standard 2 is secured a gear casing 5 within which is a worm 6 in mesh with a worm gear 7 mounted upon a bushing 8 upon a shaft 9. The worm 6 is driven by a suitable motor not shown. Keyed upon the bushing 8 is a gear 10 in mesh with a

larger gear 11 rotatable upon a shaft 12. A clutch member 13, keyed to a bushing 14, which in turn is keyed to the shaft 12, is moved into and out of engagement with a clutch face formed in the gear 11, by means 60 of a yoke 15 upon a crank 16 operated by a handle 17. A coil spring 18 upon the crank 16 normally acts to swing the shaft and yoke to hold the clutch member 13 in engagement with the gear 11. The end of 65 the shaft 12 remote from the gear 11 is screwthreaded to receive a casting 19 which forms a closed outer end for the roller 20. Within the inner end of the roller 20 is secured a casting 21 journaled upon a hollow stud 22 preferably integral with the gear casing 5, the inner end of the roller being concentric with the shaft 12. Within the hollow interior of the stud 22 is secured one end of a steel tube 23, the outer end of 70 which is mounted within a cylindrical journal portion 24 of the casting 19.

When the clutch member 13 is in engagement with the clutch face of the gear 11, rotation of the gear will cause rotation of 80 the shaft 12 and consequently rotation of the roller 20, the inner end of the roller being journaled upon the stud 22 and the outer end of the roller being journaled upon the outer end of the tube 23. It will be 85 apparent that the roller 20 may readily be unscrewed and disconnected from the shaft 12 by rotating it in the normal direction of its movement when the gear 11 is at rest, and since there is no exterior bearing for 90 the end of the roller remote from the gear casing, removal of the roller is readily accomplished.

A shoe 25 is loosely pivoted at 26 upon the upper ends of arms 27, these arms being 95 centrally pivoted at 28 within brackets 29 secured upon or formed integral with the bracket 3. An abutment portion 30 of each bracket 29 extends upward adjacent to the arms 27, the upper end of the portion 30 100 being provided with a horizontal surface 31 adapted to receive a lug 32 formed upon the lower side of the shoe 25.

Pivotal movement of the arms 27 will cause movement of the shoe 25 toward or 105 from the roller 20. As the shoe 25 is moved away from the roller 20, the lugs 32 will come into contact with the surface 31 of the brackets 29 to limit the rotational movement of the shoe. Upon continued 110

rearward movement of the shoe, the lugs 32 will come in contact with upwardly projecting stops 33 at the rear end of the surface 31 to limit the rearward movement of the lower end of the shoe, and continued rearward movement of the arms 27 will cause the upper end of the shoe to swing outward to the position indicated in Fig. 2.

Upon the bracket 3, is journaled a shaft 10 34 provided near its outer end with a crank 35 which is located at a point about midway between the lower ends of the arms 27. Pivoted upon the crank 35 is a link member 36 provided with a headed pin 37. This 15 pin 37 is mounted within a link member 38 having axially thereof a bore 39 of a size to permit free sliding movement of the pin 37 but too small to permit passage of the head 40 of the pin 37. The link member 38 20 has a hollow interior 41 of a size to permit free movement of the head 40. The exterior of the inner end of the member 38 is screw-threaded to receive a nut 42. The member 36 has a flange 43, and surrounding the link 25 members 36 and 38 between the nut 42 and the flange 43 is mounted a coil spring 44, the tension of which may be adjusted by rotation of the nut 42 upon the member 38. The outer end of the member 38 is bifurcated to receive the central part of a bar 45 30 which is pivotally secured to the member 38 by means of a pivot pin 46.

The lower ends of the arms 27 are provided with beveled perforations 47 to receive 35 the cylindrical outer ends 48 of the bar 45. The purpose of the beveling is to permit relative angular movement between the equalizing bar 45 and the arms 27, the pivotal mounting of the center of the bar permitting swinging of the bar 45 as either 40 arm 27 moves inward or outward.

In the position of parts indicated in Fig. 3 it will be seen that the crank 35 extends substantially in line between the shaft 34 45 and the pivoted center of the equalizing bar 45, the toggle action producing a firm outward thrust upon the center of the bar 45, but the spring 44 permits the center of the bar to move toward the shaft 34 as the upper end of either of the arms 27 is forced 50 outward. It will be apparent that this provides a resilient mounting for the shoe 25, enabling it to yield to conform to material of different thickness passed between the 55 shoe and the roller 20.

The shoe 25 is heated in the ordinary way by means of a gas burner 49 within the hollow interior of the shoe.

Upon the inner end of the shaft 34, is a 60 crank 50 connected by a link 51 with a wrist pin 52 mounted eccentrically of the pivot 53 of a gear 54 in mesh with a gear 55 rotatable upon the bushing 8. Mounted within a perforation within the gear 55 is a pivoted latch 65 56 pivoted at 57 and having one end pro-

jecting beyond the end of the gear to engage within recesses 58 in a clutch member 59 keyed upon the bushing 8. A spring 60 normally tends to move the latch 56 into clutching engagement with the clutch member 59. A lever 61 is pivoted at 62 upon the casing 5, and this lever is normally held in engagement with the latch member 56 by means of a spring 63 mounted upon a link 64.

In the embodiment herein illustrated the link 64 is provided with a head 66 arranged in a convenient position upon the upper surface of the casing 5. The spring 63 is of sufficient strength to swing the lever 61 about its pivot in opposition to the resistance of the spring 60 and the latch 56 will therefore normally be held in the position indicated in Fig. 4 with its free end out of engagement with the clutch member 59.

If the operator presses downward for an instant on the head 66, the lever 61 will be swung away from the latch 56 and the spring 60 will act immediately to swing the latch upon its pivot 57 into engagement with the clutch member 59 which is constantly rotating with the bushing 8 whenever the power shaft 61 is in operation.

Rotation of the clutch 59 will cause rotation of the gear 55 carrying the latch 56, out of the range of action of the lever 61 so that even if the head 66 is immediately released, it will not engage the latch until the gear 55 has completed an entire revolution, whereupon the latch 56 travelling with the gear 55 will engage one side of the lever 61 and its free end will be forced out of engagement with the clutch member 59, whereupon the gear 55 will come to rest. The number of teeth in the gear 55 is half that of the gear 54, so that a single revolution of the gear 55 will cause a half revolution of the gear 54 and the resulting movement of the wrist pin 52 and the link 51 will swing the cranks 50 and 35 from the position shown in Fig. 2 to that shown in Fig. 3. If the head 66 is depressed again, the gear 55 will be rotated as before, returning the cranks 50 and 35 from the position shown in Fig. 3 to that shown in Fig. 2.

Movement of the cranks 50 and 35 will cause the shoe 25 to be moved toward or from the roller 20 and it will be evident that this movement will commence instantly as soon as the head 66 is pressed downward.

In the modified form of the invention illustrated in Figs. 6 and 7, a gear 67 replaces the gear 11 of the embodiment previously described, and this gear may be dished as illustrated, so that while the clutch face in engagement with the clutch member 13 may occupy the same relative location as in the previous embodiment, the gear teeth are offset for engagement with a gear 68 secured to the worm gear 7, this gear 68

having the face opposite the gear 7 provided with projections to engage recesses 69 in a clutch member 70 suitably fixed on a shaft 71 which replaces the shaft 9 of the other embodiment. A compression spring 72 presses against the opposite face of the clutch member 70. Upon the outer end of the shaft 71 is secured a crank arm 73 to which is pivoted the link 51, the other end 10 of which is pivoted to the crank arm 50 secured to the shaft 34.

A cam lever 74 is mounted upon a pivot 75 corresponding to the pivot 62 of the previous embodiment, and this cam lever 74 15 may be operated by a link 64 precisely as in the other embodiment of the invention. The outer end 76 of the cam lever 74 is beveled on the side opposite the gear 68 for engagement with the correspondingly beveled cam 20 surface 77 formed upon the clutch member 70, the downward pressure upon the beveled end 76 due to the spring at the upper end of the link 64 being sufficient to withdraw the clutch member 70 from its engagement 25 with the gear 68 in opposition to the relatively weak compression spring 72. Downward pressure on the link 64 as in the previous embodiment will swing the cam lever 74 about its pivot, thus moving the beveled end 76 away from the cam surface 30 79 on the member 70, permitting the spring 72 to slide the clutch member 70 longitudinally of the shaft 71 into engagement 35 with the clutch face of the gear 68 which is constantly rotating with the gear 7. The clutch member 70 will make a half revolution, and if the cam lever 74 has returned to its normal position the beveled surfaces upon the lever and the clutch member will 40 be brought into contact, causing the withdrawal of the clutch member 70 from its engagement with the clutch face of the gear 68. At the inner end of the cam surface 77 is a curved recess 78, and the edge of the lever 74 has a correspondingly curved portion 79 for engagement with the curved portion 78 so that as the member 70 is thrust away from the gear 68 by the engagement of the beveled surfaces, the portion 50 79 of the cam lever will be brought into contact with the recess 78 to hold the clutch member 70 and the shaft 71 from further rotation.

It will be seen that this form of clutch 55 reduces the number of gears and permits the use of a correspondingly smaller space within the gear casing 5, both factors contributing to cheapen the cost of production.

The advantages of a construction of the kind herein described will be apparent to those skilled in the art. The free open end of the roller devoid of any exterior bearing makes a much easier handling of certain pieces of clothing possible, since there is 60 nothing to interfere with the placing upon

the roller of tubular pieces such as sleeves or skirts. The unobstructed open end enables the operator to utilize only so much of the roller as is necessary or desirable, and this greatly facilitates the handling of many 70 articles.

While it will be obvious that many modifications may be made in the details of construction without departing from the principle of the invention or sacrificing its advantages, the structural details herein have been devised with a view to cheapening the cost of production, and at the same time obtaining a maximum efficiency in operation. It will be understood that I do not wish to 75 be limited to the precise details illustrated, but wish to claim my invention broadly within the full and legitimate scope of the appended claims.

I claim:—

1. An ironing machine comprising a driven revoluble roll, a tiltable ironing shoe movable toward and from the roll, levers upon which the shoe is pivotally mounted, an equalizing bar having its ends universally connected to 90 said levers, and resilient means actuating the equalizing bar, whereby the shoe is yieldably held against the roll for swinging movement about horizontal and transverse axes to adapt itself to varying thicknesses 95 of material being ironed.

2. An ironing machine comprising a driven revoluble roll, an ironing shoe movable toward and from the roll, levers upon which the shoe is tiltable for movement upon a longitudinal axis while free to swing transversely of its length, an equalizing bar having its ends loosely articulated with said levers, and resilient means connected to an intermediate portion of said 100 equalizing bar to cause the levers to hold the shoe yieldingly against the roll.

3. An ironing machine comprising a driven revoluble roll, an ironing shoe movable toward and from the roll, a pair of levers 110 upon which the shoe is pivotally mounted, an equalizing bar pivoted to each of the levers so that one lever may move in advance of the other, and means for moving the bar whereby to swing the levers to move 115 the shoe toward and from the roll.

4. An ironing machine comprising a driven revoluble roll, a tiltable ironing shoe movable toward and from the roll, levers upon which the shoe is pivoted for movement upon a longitudinal axis while free to swing transversely of its length, an equalizing bar having its ends loosely connected to said levers, means for moving the bar whereby to swing the levers to move the shoe toward 120 and away from the roll, and abutments engageable by said shoe to cause tilting thereof when actuated by said levers.

5. An ironing machine including a casing, 125 a hollow stud protruding from said casing,

- a power driven shaft protruding from said casing through said stud and having an outer free end, a tube fixed in said stud and through which extends said shaft, and a roll about said tube, said roll having its outer end rotatably supported on said tube and driven from the free end of said shaft said roll having its inner end rotatably supported on the hollow stud of said casing.
- 10 6. An ironing machine comprising a revoluble roll supported at one end only, driving means at the supported end of said roll for revolving it, an ironing shoe movable toward and from the roll, a pair of levers upon which the shoe is pivotally mounted, an equalizing bar having its ends loosely connected to each of the levers, and means for moving the bar including a crank shaft, a toggle connection between the crank shaft and the bar, and means actuated from said

roll operating means for rocking the shaft whereby to move the levers to press the shoe against the roll.

7. An ironing machine comprising a driven shaft, a casing in which one end of the shaft is journaled, a hollow stud having an outer cylindrical surface concentric with the shaft, a tube secured within the stud and surrounding the shaft, a roll having two end members, the one adjacent to the casing having an opening in its end concentric with the axis of the roll and mounted for rotation upon the outer cylindrical surface of the stud, the other end member having an axial recess in threaded engagement with the outer end of the driven shaft and a second recess concentric with the shaft to receive the outer end of the tube.

In testimony whereof I affix my signature.
THOMAS J. ARBRON.
